UNITED STATES PATENT OFFICE.

FREDERICK C. MOSSER, OF ALLENTOWN, PENNSYLVANIA.

SANDING DEVICE.

1,201,853.

Specification of Letters Patent.

Patented Oct. 17, 1916.

Application filed April 12, 1916. Serial No. 90,623.

To all whom it may concern:

Be it known that I, FREDERICK C. MOSSER, a citizen of the United States, residing at Allentown, in the county of Lehigh and 5 State of Pennsylvania, have invented certain new and useful Improvements in Sanding Devices; and I do hereby declare the following to be a full, clear, and exact description of the invention, such as will enable others skilled in the art to which it 10 appertains to make and use the same.

The primary object of this invention is to provide a novel type of connection between the hopper and the discharge spout of a track sanding device for a car, that will 15 admit of the discharge spout being carried by the car truck and follow the rails of the track when the car is turning a curve.

Another object of the invention is to 20 provide a device for carrying out the above object, which will be of simple and durable construction and efficient in operation.

Other objects will appear and be better understood from that embodiment of my 25 invention of which the following is a specification, reference being had to the accompanying drawing forming a part thereof, in which:

Figure 1 is a sectional view of a car body, 30 and showing the sanding device applied thereto, Fig. 2 is a vertical sectional view, taken through the sanding device removed from the car body, Fig. 3 is a transverse section, taken on the line 3—3 of Fig. 2, Fig. 4 is 35 a longitudinal sectional view, taken through the inner slidable section of the discharge spout, and Fig. 5 is a horizontal section, taken on the line 5—5 of Fig. 2.

Referring to the drawing in detail, the 40 letter A designates a car body and B one of the car trucks located at one end of the car body.

The numeral 1 designates a hopper for holding sand, and which can be positioned 45 at any point on the body of the car. As shown in the drawing, the hopper has its discharge end extending through an opening in the floor of the car and connected in any suitable manner with the upper end of 50 a vertically disposed flexible discharge tube 2.

A discharge spout is associated with the car truck B, and consists of a pair of telescoping sections designated, respectively, by 55 the numerals 3 and 4. The discharge spout is extended inwardly at an angle to the

forward cross bar of the car truck, and the outer section 3 has its upper end enlarged, as shown at 5, to provide an internal annular shoulder 6. A lateral extension 7 is 60 formed on the upper end of the section 3 and has a straight side 8 thereon, which engages against the adjacent inner face of the forward cross bar of the truck frame B, as shown in Figs. 2 and 5 of the drawing, 65 the said extension having a pair of ears 9 formed thereon, which have connection with the forward cross bar of the frame B by means of the fastening bolts 10. The section 4 of the spout is slidable within the 70 section 3 and has its upper end enlarged, as shown at 11, to provide the shoulder 12, which is adapted to normally rest on the shoulder 6 formed on the lower or outer section 3, so as to limit the downward movement of the inner section 4. The lower or inner end of the section 4 is terminally disposed above the lower terminal of the section 3, and the upper end of the section 4 is terminally extended above the upper end 75 of the section 3 and is provided with an annular seat 13. The lower end of the flexible tube 2 engages over the upper end of the inner section 4 and covers the seat 13, and a split metallic band 14 encircles 80 the lower end of the tube 2 and the adjacent end of the section 4, and depresses a portion of the tube 2 within the seat 13, so as to secure the section 4 to the tube 2, the said band having its opposite ends provided with apertured ears 15, through 85 which pass fastening bolts 16 for securing the band 14 in position.

The lower end of the section 3 of the discharge spout is provided with an annular 90 rib 17, which reinforces the lower terminal of the section 3 and prevents injury being done to the lower end of the section 3, when the same comes in contact with an 95 obstacle.

A suitable valve, not shown, can be associated with the discharge end of the sand box 1 so as to cut off the flow of sand from the sand box into the discharge spout, said valve being adapted to be operated by 100 means of suitable operating mechanism 18 carried by the platform of the car body.

What I claim is:

1. The combination with a car body and a car truck, and a hopper carried by the 110 car body and disposed above the truck, of a flexible tube having one end secured to

- the lower end of the hopper, a discharge spout formed of a pair of telescoping sections, the innermost section having connection with the other end of the flexible tube 5 so as to establish communication between the hopper and the spout, and means for connecting the outermost section of the spout to the car truck.

2. The combination with a sand hopper 10 having a flexible discharge tube, of a discharge spout formed of a stationary outer section and a slideable inner section, means for limiting the sliding movement of the inner section in one direction, and means 15 for connecting one end of the inner section to one end of the flexible tube.

3. The combination with a car truck and a hopper disposed above the truck and having a flexible discharge tube depending in 20 the direction of the truck, of a discharge spout formed of a stationary section and inner slideable section, means for connecting one end of the inner section to the

lower end of the flexible tube, an extension formed on the stationary section, and means 25 for connecting the extension to the car truck.

4. The combination with a car truck frame and a hopper disposed above the frame and having a flexible depending discharge tube, of a discharge spout carried by the car truck frame and formed of an outer stationary section and an inner slideable section, one end of the slideable section being received by the lower end of the tube 35 and having an annular seat formed therein, and fastening means encircling the lower end of the tube for depressing a portion of the tube in the seat on the slideable section.

In testimony whereof I affix my signature in presence of two witnesses.

FREDERICK C. MOSSER.
